UNITED STATES PATENT OFFICE.

WILLIAM WHITE, OF NEW YORK, N. Y., ASSIGNOR TO CLARENCE WHITMAN & CO., OF SAME PLACE.

DESIGN FOR A BEDSPREAD.

SPECIFICATION forming part of Design No. 23,491, dated July 24, 1894.

Application filed June 26, 1894. Serial No. 515,793. Term of patent 3½ years.

To all whom it may concern:

Be it known that I, WILLIAM WHITE, a citizen of the United States, residing in the city, county, and State of New York, have invented and produced a new and original Design for Bedspreads, of which the following is a specification, reference being had to the accompanying drawing, which represents a face view of a portion of a bedspread embodying my design, part only being shown in detail, the remainder being shown in outline.

The essential feature of my design is a bedspread ornamented in its field with a series of star-like configurations surrounded by scroll-like bands, and with conventional leaf-like configurations and juxtaposed scroll-like bands, and with an ornamental border presenting a striped effect or configuration.

In the drawing *a a* are series of star-like

ornamental configurations surrounded by scroll-like bands *b b*. Adjacent to these star-like ornaments are conventionalized leaf-like ornamental configurations *c c c* with juxtaposed scroll-like bands *d d*. The border is composed of bands or stripes *e e f f* presenting a striped effect or configuration. The field within the border between the scroll-like bands and the ornamental leaf-like and star-like configurations, is filled in with check and lattice configurations or effects *g h*, respectively.

What I claim is—

The design for a bed-spread substantially as herein shown and described.

WILLIAM WHITE.
